US00D862228S

(12) **United States Design Patent** (10) **Patent No.:** **US D862,228 S**
(45) **Date of Patent:** **** Oct. 8, 2019**

(54) **CUP LID**

(71) Applicant: **HANGZHOU EVERICH HOUSEWARE CO., LTD.**, Hangzhou, Zhejiang (CN)

(72) Inventor: **Huajun Yao**, Zhejiang (CN)

(73) Assignee: **EVERICH AND TOMIC HOUSEWARES CO., LTD.**, Jianggan District, Hangzhou, Zhejiang (CN)

(**) Term: **15 Years**

(21) Appl. No.: **29/624,584**

(22) Filed: **Nov. 2, 2017**

(51) **LOC (12) Cl.** **09-07**

(52) **U.S. Cl.**

USPC **D9/443**; D7/392.1

(58) **Field of Classification Search**

USPC D7/300.1, 387, 388, 391, 392, 392.1, D7/393, 394, 395, 396.1, 396.2, 396.6, D7/397, 398, 403, 509, 510, 511, 566, D7/624.1, 625, 672, 900; D9/434, 435, D9/436, 437, 438, 443, 448, 449, 450, D9/451, 454, 453, 516, 529, 548, 685, D9/686, 723, 730, 763; D8/300, 303, D8/330, 354, 356, 382, 396; D23/206, D23/209, 259, 260, 365; D24/121, 127, D24/194, 196; D34/1, 7, 10, 11; D32/68, 70, 72

(57) **CLAIM**

The ornamental design for a cup lid, as shown and described.

DESCRIPTION

FIG. 1 is a front elevational view of a cup lid, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top perspective view thereof; and,

FIG. 8 is a bottom perspective view thereof.

1 Claim, 4 Drawing Sheets
